UNITED STATES PATENT OFFICE.

WILLIAM C. SCHEU, OF LOS ANGELES, CALIFORNIA, ASSIGNOR TO HARRISON, PAUL SCHEU CO., OF UPLAND, CALIFORNIA, A CORPORATION OF CALIFORNIA.

GAS GENERATOR.

Application filed June 18, 1921. Serial No. 478,608.

To all whom it may concern:

Be it known that I, WILLIAM C. SCHEU, a citizen of the United States, residing at Los Angeles, in the county of Los Angeles and State of California, have invented a new and useful Gas Generator, of which the following is a specification.

My invention relates to devices for producing combustible mixtures of air and fuel 10 from liquid hydrocarbons, such as petroleum or petroleum distillates.

An object of my invention is to produce a combustible mixture by heating a mechanically actuated column of air and injecting 15 therein the liquid fuel or oil.

A further object of the invention is to provide an apparatus in which such a combustible mixture may be generated without the deposition of carbon or tarry matter in 20 the apparatus.

With such objects in view, as well as other advantages which may be incident to the use of the improvements, the invention consists in the procedure, and in the parts and 25 combinations thereof hereinafter set forth and claimed, with the understanding that the several necessary elements constituting the same may be varied in proportions and arrangements without departing from the 30 nature of the invention.

In order to make the invention more clearly understood there are shown in the accompanying drawings means for carrying the same into practical effect, without limiting 35 the improvements in their useful applications, to the particular constructions which, for the purpose of explanation, have been made the subject of illustration.

Further objects and advantages will be 40 made evident hereinafter.

Referring to the drawing which is for illustrative purposes only;

Fig. 1 is a plan view of an arrangement of apparatus embodying my invention.

Fig. 2 is a side elevation of the burner shown in Fig. 1 with the lower portion thereof in section on a plane represented by the line 2—2 of Fig. 1.

Fig. 3 is a fragmentary sectional view 50 taken substantially upon a plane represented by the line 3—3 of Fig. 1.

Fig. 4 is a horizontal sectional view to illustrate the interior construction of the heat-

ing chamber 1 employ, taken on a plane represented by the line 4—4 of Fig. 2.

Fig. 5 is an elevation of my invention incorporated in a burner having a broad field of application.

A hollow ring 11 providing a circular chamber 12 and having at a suitable point 60 therein a web or wall 13 is provided with a threaded inlet 14 and a threaded outlet 15. Upwardly projecting from the inlet 14 is a short nipple 17 which mounts an elbow 18 into which is threaded an air delivery pipe 65 19 leading from a blower 20 or other suitable source of air supply. Within the air pipe 19 is an oil nozzle 21, a projecting portion 22 of which makes connection with an exterior oil supply line 23 in which is situated a valve 24. Rising from the outlet 15 of the hollow ring 11 is a nipple 25 mounting a branch fitting 26 having opposing outlets 27 and 28 and an inlet arm 30 adapted 70 for connection with a pipe extending parallel to the nipples 35 and 36 which are screwed into the outlets 28 and 27 respectively. Upon the lower end of the nipple 35 is a burner cap 40 having laterally extended orifices 41, and upon the upper end of the 75 nipple 36 is located an elbow 42 from which leads a gas delivery pipe 43. The generator rests in a firing pan 45 and is shown in the application which I have chosen for illustrating the embodiment of my invention, 80 that of generating gas for remote consumption or delivery to a suitable storage through the delivery pipe 43.

When starting the generator a small quantity of oil is allowed to flow into the pan 45 and ignited, the flames arising therefrom serving to heat the ring 11 and the remaining parts of the generator situated above the pan 45. The motor 50, driving the blower 20, is then started to cause a flow of air into 90 the generator through the pipe 19, and the valve 24 in the oil line 23 is opened to allow a flow of oil through the nozzle 21. The air stream in passing through the elbow 18 picks up the oil from the nozzle and carries same down into the chamber 12 of the hollow ring 11 through the nipple 17.

Entering the chamber 12, the air and oil assume the course indicated by the arrows in Fig. 4 and during their passage therethrough are raised in temperature due to 100

the heated condition of the ring 11. Rising through the heated nipple 25 the vaporized oil and its then intermixed propelling air stream pass the fitting 26, a portion thereof 5 passing upwardly through the nipple 36 and the elbow 42 is carried to its point of consumption through the delivery pipe 43. The remaining portion of the mixture passes through the column formed by the nipple 35 10 and passes out through the orifices 41 provided in the burner cap 40. The burner cap 40 is situated slightly beneath the ring 11 as illustrated in Fig. 2 and delivers a spreading flame against the underside of the ring 15 11 to furnish the necessary heat for vaporizing the fuel after the burner is once put into operation. The orifices 41 are made of a size capable of delivering a flame sufficiently large to furnish the required amount of heat 20 for the vaporization of the particular oil used.

My device may be readily transformed into a self generating oil burner, as shown in Fig. 5, by mounting a burner head 55 25 upon the nipple 36, this burner head being provided with lateral openings 56 to throw a spreading flame. Air ports 57 are provided in the dished flange 58 to furnish additional air to support combustion. In this 30 adaptation, as in the previously described embodiment of my invention, a portion of the gas generated in the ring 11 is consumed by the burner 40 while the greater part of the gas is consumed at the burner 55 and 35 the heat thereof is applied directly to its point of utility.

The improved generating burner forming the subject matter of this application is particularly adapted to the conversion of the 40 heavier oils to a combustible gas. This conversion being accomplished without the usual deposition of carbonaceous materials ordinarily attending the breaking down of these heavier oils. I attribute this valuable 45 result very largely to the use of large passageways that are not restricted in any manner by filters and mixing devices. The comparatively large volume of gas always in contact with the walls of the burner members and the various pipes, seems to contain sufficient heat to practically prevent condensation with the resultant deposition of the 50 heavier residues of the oil.

On account of the comparatively large 55 pipe areas the burner of this invention is also particularly adapted to handle other types of fuels, such as coal in powdered form which could be injected into the chamber 11 with the air entering therein. The chamber 60 11 constitutes not only a vaporizing chamber, but also a fuel and air mixing and heating chamber, the fuel being mixed by reason of the rapid circulation of the air through the said chamber while the fuel is introduced 65 therein.

I claim as my invention:

1. A gas generator comprising a generating burner, a burner inlet pipe extending downwardly to the burner, a generating chamber extending around said inlet pipe and burner and having an outlet extending upwardly and connecting with the downwardly extending inlet pipe for the burner, a gas outlet means connecting with said outlet of the generating chamber, and an outlet pipe communicating with said chamber at the end thereof remote from the outlet of said chamber, means for forcing air to said air inlet pipe, and means for supplying fuel to said air inlet pipe. 70 75 80

2. A gas generator comprising a generating burner, a burner inlet pipe extending downwardly to the burner, a generating chamber extending around said inlet pipe and burner and having an outlet extending upwardly and connecting with the downwardly extending inlet pipe for the burner, a gas outlet means connecting with said outlet of the generating chamber, and an outlet pipe communicating with said chamber, at the end thereof remote from the outlet of said chamber, means for forcing air to said air inlet pipe, and means for supplying fuel to said air inlet pipe, said fuel supply means comprising a pipe extending within said air inlet pipe to a point adjacent to the inlet of the generating chamber, so as to protect the fuel inlet pipe from the direct heat of the burner. 85 90 95

3. A generating burner comprising a hollow ring of large cross sectional area and having a partition therein, means for forcing a mixture of air and a heavy oil into said ring, means for drawing a combustible gas from said ring, and conveying a portion of it through large area pipe means to a burner where it is consumed and serves to heat said hollow ring to thus produce a continuous generation of combustible gas, large cross sectional area pipe means for conveying the generated gas not consumed at said burner to a place of storage or to other burners, said hollow ring and all of said pipe means having free and unobstructed passageways whereby the accumulation of carbonaceous residues is obviated. 100 105 110 115

4. A generating burner comprising a hollow ring of large cross sectional area having inlet and outlet openings with an imperforate partition therebetween, means for forcing a mixture of air and heavy oil into said hollow ring on one side of said partition, means for drawing a combustible gas from said hollow ring on the other side of said partition, large cross sectional area pipe means for receiving said gas and conveying a portion to a burner where it is consumed and serves to heat said ring and permit of a continuous generation of combustible gas, and conveying the remainder to a burner 120 125 130

- where it is consumed and serves to supply heat for any desired purpose, said hollow ring and all of said pipe means having free and unobstructed passageways whereby the accumulation of carbonaceous residue is obviated.
5. A pan for containing a preheating fuel, a hollow ring positioned in said pan, said ring having inlet and outlet openings with a partition therebetween, means for passing a mixture of air and heavy oil into said hollow ring through one of said openings and for drawing a combustible gas from said hollow ring through the other of said openings, large area pipe means for conveying a portion of said gas to a burner located adjacent said hollow ring where it is consumed, thereby heating said ring to form the said combustible gas, and large area pipe means for conveying the remainder of said generated gas to other sources of combustion, said hollow ring and all of said pipe means having free and unobstructed passageways whereby the heat of the moving gas, is maintained and the accumulation of carbonaceous residue is obviated.
10. A generating burner comprising a hollow ring of large cross sectional area and having a partition therein, means for passing a gas producing fuel into said hollow ring, large area pipe means for drawing a combustible gas from said ring and conveying a portion to a burner located adjacent said hollow ring where it is consumed and serves to heat said ring, said pipe means conveying the unconsumed portion of said gas to another place of consumption, said hollow ring and all of the said pipe means connected therewith having free and unobstructed passageways whereby the heat of the moving gas is maintained and the accumulation of carbonaceous residue is obviated.
15. In testimony whereof, I have hereunto set my hand at Los Angeles, California, this 13th day of June, 1921.
20. WILLIAM C. SCHEU.
